UNITED STATES PATENT OFFICE.

JOHN WARREN VEDDER, OF WORCESTER, MASSACHUSETTS.

STONE PRESS ROLLS.

1,413,436.

Specification of Letters Patent. Patented Apr. 18, 1922.

Application filed January 12, 1920. Serial No. 350,861.

To all whom it may concern:

Be it known that I, JOHN WARREN VEDDER, a citizen of the United States of America, and a resident of Worcester, Massachusetts, 5 have invented new and useful Improvements in Stone Press Rolls, which invention is fully set forth in the following specification.

This invention relates to improvements in press-rolls for paper-making machines, and 10 more particularly to stone press-rolls between which the paper is passed after leaving the couch-rolls.

Heretofore stone press-rolls of the above character have been mounted on metal shafts 15 and secured thereto by cement and by end collars. Press-rolls thus constructed have the serious objection of cracking when for any cause their bearings become heated.

The heat developed at the end supports of 20 the shaft is conducted to the interior of the roll causing the stone to expand and give way under the internal strains. Furthermore, by reason of the weight of such rolls, difficulty is experienced in properly adjusting them to avoid crushing the newly formed 25 sheet of paper as it passes with its felt support between the rolls.

The primary object of this invention is to provide effective means for preventing this 30 injurious action of heat on the stone material of the rolls and to lighten the construction while retaining the advantages of the use of the stone-surfaced rolls.

A further object of the invention is to 35 improve the manner of mounting the stone on its supporting shaft and in securing the shaft to the stone. The above and other objects will be more fully explained in the detailed description.

With the above objects in view, my invention resides in mounting the stone which is 40 to form the roll on a tubular metal shaft, preferably of forged steel, the heat radiating-surface of which is sufficient to dissipate to the air or other fluid in or passed 45 through the hollow shaft, the injurious excess of heat produced at the shaft bearings. The ends of the tubular shaft may be open 50 to the atmosphere or may be in communication with a source of cooling fluid. The size of the tubular shaft in relation to that of the roll may vary within comparatively wide limits. I have found, for example, that the relation of about 1 to 3 for the 55 diameters of the tubular shaft and stone roll gives good results. The tubular shaft

may be secured to the stone in any suitable manner but I prefer to employ for this purpose my improved means the construction of which is described below. Before mounting the stone on the shaft, centering plugs, either tapered or straight but preferably 60 perforated, are inserted in the end openings of the shaft which is then supported in a lathe and the end portions are turned and 65 threaded. The roll is then mounted on the shaft and subjected to a machining operation.

In order that the invention may be more readily understood, reference is had to the 70 accompanying drawings which show, by way of example, two constructional forms of the invention; such drawings, however, are intended to assist the description and not as defining the limits thereof.

In said drawings:

Fig. 1 is a view of a press-roll, partly in longitudinal section and partly in side elevation, showing one embodiment of my invention; and

Fig. 2 is a similar view to Fig. 1 showing a modification.

Referring to Fig. 1 of the drawings, 1 is a tubular metal shaft preferably consisting of a forged steel tube, the ends of which are 85 adapted to receive centering plugs 2 preferably tapering and provided with openings 3. Both ends of the shaft being alike, the description will be confined to one end only. Mounted on shaft 1 is a stone roll body 4, 90 the central bore in which terminates in an enlarged opening 5 here shown as flaring or cone-shaped, though it may assume other forms as straight shown in Fig. 2. 6 is a bushing or sleeve fitting opening 5 and extending beyond the face of the roll. This bushing may be secured in position between shaft 1 and roll 4 by a forced fit, but I preferably provide the shaft with threads as shown and screw the bushing home on the 100 shaft. 7 is a metal collar or flange mounted on and fitting about the protruding end of the bushing and preferably having a threaded engagement therewith. Where the flange faces the end of the stone roll, the flange 105 is cup-shaped or dished to receive the conical end of the roll, thereby taking some of the side stress which tends to crack the bushing and also the roll. The flange 7 may be and preferably is fastened in place by a securing pin of which two are shown in Fig. 110 1; they not only secure the collar to the

bushing against relative movement, but likewise secure the bushing to the shaft.

The roll as thus constructed is assembled by inserting the shaft 1 through the opening 5 in the stone member with both ends of the shaft protruding beyond the stone body to constitute bearing members the exterior bearing surfaces of which are adapted to make rotatable engagement with suitable 10 supporting bearing members not shown. Wedges or bushings 6 are slipped over the ends of the shaft and screwed to a tight fit between the shaft and the stone, and then the collars 7 are placed in position against 15 the ends of the roll and secured on the ends of the bushings. The roll is then placed in a lathe and supported by means of centering plugs 2 and the surface is machined.

In operation, the end plugs in the tubular 20 shaft may be, and preferably are, removed to facilitate air circulation, or the shaft may be connected to a source of cooling fluid not shown. The heat developed at the bearings of the shaft is conducted away from the ends 25 of the roll and more particularly from the bearing surfaces on the projecting ends of the shaft by means of the good heat conducting metal wall of the shaft and distributed to the interior surface of the shaft 30 by which it is dissipated to the air or fluid within the hollow shaft. Thus, this heat is not permitted to accumulate and raise the temperature of the stone, but is, by reason of the construction, transferred to the air or 35 other fluid medium in the tube and removed either by air convection currents set up in the tube or by passing a cooling fluid through the hollow shaft. In this manner the ends and other parts of the stone are 40 kept below a temperature which produces breaking stresses in the stone. Even with the perforated centering plugs in position the benefits of cooling are manifest.

The replacement of a solid forged steel 45 shaft, as heretofore employed, by a forged steel tube results in materially reducing the weight of the roll without sacrificing strength and rigidity, thereby permitting the rolls to be operated without crushing the 50 paper.

By reason of the wedge construction as described, the stone is made fast to the shaft by a close fit of the wedge before applying the cupped flange or collar.

55 In the constructional form shown in Fig. 2, the central opening in the stone roll 4' is slightly larger than the tubular shaft 1' for the purpose of receiving a cementing material such as grouting or other like material 60 10 which fills the space between the shaft and roll. The central opening in the stone is enlarged at each end to receive cylindrical bushings 11 which are provided with perforated flanged portions which may be integral 65 with the bushing as shown or may be

separate therefrom as shown in the constructional form, Fig. 1.

Before placing the bushing in position, wire 9 is preferably wrapped around the body portion of the bushing, leaving enough 70 wire free to form a spiral wrapping between the flange portion of the bushing and the end of the stone roll. The wire-wrapped bushing, together with a suitable quantity of cement, is inserted over the shaft and placed 75 in position in the enlarged opening of the roll, leaving a space between the flange portion of the bushing and the roll for receiving a few turns of wire and cement. The flanged bushing is made fast to the shaft by any suitable 80 means, such as by a pin 12. To ensure that the cement space may be entirely filled, cement for this purpose is introduced through the perforations in the flange. It is found that the wire embedded in the cement assists in retaining the cement by preventing its disintegration, and also in strengthening the joint between the shaft and stone where it is subject to the greatest 85 stress. One or more side openings are preferably provided in the shaft for receiving porous plugs, such as wooden plugs 13, which permit moisture to escape from the cement and for preventing accumulation of vapor pressure in the cement space. 95

What I claim is:—

1. A press-roll comprising a stone surface portion having a central bore, a tubular metal shaft the end portions of which constitute bearings and the central portion of which is adapted to enter said bore, said shaft having an internal heat-dissipating surface adapted to dissipate heat generated in the roll bearings, said surface being in good heat transmitting relationship with said bearings entirely through material of good heat conductivity, and bushings provided with collars bearing against the ends of said stone portion. 100

2. A press-roll comprising a stone surface portion having cone-shaped ends and a central bore with flaring end openings, a tubular metal shaft the end portions of which constitute roll bearings and the central portion of which is adapted to enter said bore, said shaft having an internal heat-dissipating surface adapted to dissipate heat generated in said roll bearings, tapering bushings having threaded engagement with said shaft and adapted to enter said flaring openings, and cup-shaped retaining collars adapted to be secured to said bushings and fit over the conical ends of said stone portion. 110

3. In a roll, the combination of a stone body portion, a tubular shaft secured to and extending longitudinally through said stone body portion and by reason of its tubularity having an internal surface adapted to dissipate heat, and a bearing member at one or 125 130

both ends of said shaft adapted to make rotatable engagement with a supporting bearing member and having its bearing surface in heat communicating relationship to said 5 internal surface of the shaft through a path of good heat conductivity adapted to conduct heat from the bearing to said internal surface of the shaft.

4. In a roll, the combination of a stone 10 body portion, a tubular shaft secured to and extending longitudinally through said stone body portion and by reason of its tubularity having an internal surface adapted to dissipate heat, and a bearing member at one or 15 both ends of said shaft adapted to make rotatable engagement with a supporting bearing member and having its bearing surface in heat communicating relationship to said internal surface of the shaft through an 20 all metal path of good heat conductivity adapted to conduct heat from the bearing to said internal surface of the shaft.

5. In a roll, the combination of a stone 25 body portion, a tubular shaft secured to and extending longitudinally through said stone body portion and projecting at one or both ends thereof with the surface of said projecting shaft end constituting a bearing surface adapted to rotate in engagement with a 30 supporting bearing member and said shaft by reason of its tubularity having an internal surface adapted to dissipate heat communicated thereto through the metal of the shaft from the bearing surface at the end 35 thereof.

6. In a roll, the combination of a stone 40 body portion having an axial bore, a tubular metal shaft extending through said axial bore and projecting at both ends of the stone body portion to constitute bearings on the roll for engagement with supporting bearings, means securing said body to said shaft, and centering plugs in the ends of the tubular shaft for centering and supporting the 45 roll in the finishing of the surface of its stone body.

7. In a roll, the combination of a stone 50 body portion having an axial bore, a tubular metal shaft extending through said axial bore and projecting at both ends of the stone body portion to constitute bearings on the roll for engagement with supporting bearings, means securing said body to said shaft, and perforated centering plugs in the 55 ends of the tubular shaft for centering and supporting the roll in the finishing of the surface of its stone body.

8. In a roll, the combination of a stone 60 body portion having a central bore, a shaft extending through said central bore, and means securing said stone body to said shaft said means including, at one or both ends of the roll, a bushing or sleeve on the shaft closely fitting within the bore of the stone 65 body at one end thereof, the outer end of

said bushing projecting beyond the end surface of the stone body, and a separately formed annular collar fitting about and secured on said projecting end of the bushing and adapted to be applied in said position after the bushing has been properly positioned with reference to the stone body. 70

9. In a roll, the combination of a stone body portion having a central bore, a shaft 75 extending through said central bore, and means securing said stone body to said shaft said means including, at one or both ends of the roll, a bushing or sleeve on the shaft closely fitting within the bore of the stone body at one end thereof, the outer end of 80 said bushing projecting beyond the end surface of the stone body, and a separately formed annular collar fitting about and secured on said projecting end of the bushing and having a dished surface for engagement 85 with a corresponding surface on the end of the stone body, said collar being adapted to be thus positioned after the bushing has been properly positioned with reference to the stone body. 90

10. In a roll, the combination of a stone body portion having a central bore, a shaft 95 extending through said central bore, and means securing said stone body to said shaft said means including, at one or both ends of the roll, an exteriorly tapering bushing or sleeve on the shaft closely fitting within the similarly shaped bore of the stone body at one end of the latter, the outer end of 100 said bushing projecting beyond the end surface of the stone body, and an annular collar fitting and secured on said projecting end of the bushing.

11. In a roll, the combination of a stone body portion having a central bore, a shaft 105 extending through said central bore, and means securing said stone body to said shaft said means including, at one or both ends of the roll, a bushing or sleeve in screw-threaded engagement with the shaft and closely 110 fitting within the bore of the stone body at one end thereof the outer end of said bushing projecting beyond the end surface of the stone body, and an annular collar fitting and secured on said projecting end of the bushing. 115

12. In a roll, the combination of a stone body portion having a central bore, a shaft 120 extending through said central bore, and means securing said stone body to said shaft said means including, at one or both ends of the roll, a bushing or sleeve in screw-threaded engagement with the shaft and closely fitting within the bore of the stone body at one end thereof the outer end of said bushing 125 projecting beyond the end surface of the stone body, and an annular collar in screw-threaded engagement with said projecting end of the bushing.

13. In a roll, the combination of a stone 130

body portion having a central bore, a shaft extending through said central bore, and means securing said stone body to said shaft said means including, at one or both ends of 5 the roll, an exteriorly tapering bushing or sleeve in screw-threaded engagement with the shaft and closely fitting within the similarly shaped bore of the stone body at one end thereof, the outer end of said bushing 10 projecting beyond the end surface of the stone body, and an annular collar making screw-threaded engagement with the projecting end of said bushing.

14. In a roll, the combination of a stone body portion having a central bore, a shaft extending through said central bore, and means securing said stone body to said shaft said means including, at one or both ends of 15 the roll, an exteriorly tapering bushing or sleeve in screw-threaded engagement with the shaft and closely fitting within the similarly shaped bore of the stone body at one end thereof, the outer end of said bushing 20 projecting beyond the end surface of the stone body, and an annular collar making 25

screw-threaded engagement with the projecting end of said bushing and having a cor- 30 dished face for engagement with a corresponding surface on the end of the stone body.

15. In a roll, the combination of a stone body portion having a central bore, a shaft extending through said central bore, and means securing said stone body to said shaft said means including, at one or both ends of 35 the roll, a bushing or sleeve on the shaft closely fitting within the bore of the stone body at one end thereof, the outer end of said bushing projecting beyond the end surface of the stone body, an annular collar fitting and secured on said projecting end of the bushing, a pin engaging registering openings in the bushing and shaft to secure the same against relative movement, and a pin engaging registering openings in the 40 collar and bushing to secure the same against relative movement.

In testimony whereof I have signed this specification.

JOHN WARREN VEDDER.
